ATTORNEY

UNITED STATES PATENT OFFICE.

JOSEPH TIRITTER, OF BROOKLYN, NEW YORK.

ERASER REEL.

Application filed April 23, 1926. Serial No. 104,015.

The main object of this invention is to provide a device applicable to typewriters which supports an eraser at a position adjacent the typewriter and permits adjustment of the eraser to any position upon the cylinder.

Another object is to provide an eraser reel which is mounted upon the frame of a typewriter and permits extensibility of a cord from which an eraser is suspended to any position on the typewriter cylinder, and immediately after release of the eraser, the latter is retracted toward the reel where it remains in convenient position until it is again used.

Still another object of the invention is to provide means on the eraser reel for securely clamping the entire device to the frames of various types of typewriters.

The above and other objects will become apparent in the description below, in which characters of reference refer to like-named parts in the drawing.

Referring briefly to the drawing, Figure 1 is a perspective view, showing a corner of a typewriter having the eraser reel mounted in place thereon.

Figure 2 is a longitudinal sectional elevational view of the reel for the typewriter eraser.

Figure 3 is an end elevational view of Figure 2.

Figure 4 is a top plan view of Figure 2.

Figure 5 is a front elevational view of a modified type of device.

Referring in detail to the drawing, the numeral 10 indicates the side of a frame which bounds the keys 11 on three sides. Within the area bounded by this frame, the space bar 12 and other movable elements are depressible. On the side of the frame, a casing, consisting of two members, a lower cap 13 and an upper cap 14 is mounted. The bottom of the lower cap 13 has a post 15 extending upwardly into the chamber 16 formed by the upper and lower caps. The upper cap has a screw 17 which shoulders in the roof of the upper cap and is engaged in a threaded opening in the post 15 for the purpose of securing the upper and lower caps to each other. A drum 18 is mounted rotatably on the shank of the screw 17 and has the coils 19 of an endless cable wound upon its periphery. The drum 18 is open at the bottom so that it can receive the spiral

spring 20, one end of which is attached to the drum, the opposite end being secured to the post 15. The end of the cable 19 coursing from the periphery of the drum 18 emerges from the casing thru an opening 21 and has a fastening means 22 attached thereto which may be secured in an opening formed in the usual type of typewriter eraser 23.

The typewriter reel, consisting of the casing and its contained elements, is adapted to be detachably mounted upon any type of typewriter frame. This mounting means consists of a rigid tongue 24 which projects radially from the side of the bottom cap 13 and its extending end is formed into an upwardly bent hook 25. A similar tongue 26 having a hook 27 forming part thereof is fixed in an adjustable manner upon the upper cap 14. The tongue 26 is supported upon studs 28 and 29 which project upwardly from the roof of the cap 14 and the upper ends of these studs have inclined edges which end abruptly, as illustrated in Figure 2. Around these studs, a housing consisting of side walls 30 and a roof 31, is formed. A pair of studs 32 and 33 are mounted on this roof 31 and extend downwardly therefrom, being separated by a space from the lower studs 28 and 29 into which space the tongue 26 is slipped. Intermediate the length of the tongue 26, an opening is provided thru which a reduced portion of the threaded shank 34 of a screw is rotatably mounted. Said screw is provided with a head 35 which rises above the roof 31 of the housing and is adapted to be manipulated by the fingers when mounting the device upon a typewriter by deflecting the tongue upwardly or downwardly to vary the distance between the hooks 25 and 27 of opposing tongue members. The reduced portion of the shank 34, which is rotatably mounted in the tongue 26, has a head 36 formed thereon and the threaded shank 34 is rotatably and threadably mounted in an opening formed in the roof 31.

The device comprises a typewriter reel which at all times positions an eraser in the same place. In use, the eraser 23 is grasped and pulled on until the cable 19 unwinds itself to permit the eraser to be placed over the position where it is desired to be used. After use of the eraser, the same is released from the hand and the spiral spring 110

20 being tensioned by paying out of the cable 19, yieldably rotates the drum 18 in an opposite direction and again winds the cable 19 upon the drum 18, thus automatically removing the eraser from the position in which it was used to its position beside the side 10 of the typewriter frame. The means for mounting the reel to a typewriter frame is made adjustable to compensate for various 10 heights of frames on different types of typewriters. This means includes the rigid tongue 24 mounted on one cap 13 and a flexible tongue 26 which is supported between bottom studs 28 and 29 and upper studs 32 15 and 33. The portion of the tongue 26 between the studs 28 and 29 is flexed either upwardly or downwardly according to the rotation of the shank 34 of the screw. This causes flexing in one direction or the other 20 of the projecting hook end 27 of the screw and by this flexing, the distance between the hooks 25 and 27 is varied. When desiring to reduce the distance between the hooked 25 ends of the tongues, the shank 34 of the screw is raised and when increasing this distance, opposite rotation of the shank 34 is required.

Figure 5 represents a modified type of device having some parts thereof similar to that of the preferred form, which similar parts will be numbered by the same numerals. The upper member 14 is provided with a pair of lugs 36^a and 37 which have aligned threaded openings therein for reception of a screw 38 having a hook 39 at one end and a head 40 at its opposite end. By turning or rotating the screw 38, the hook 39 is brought into engagement with the part 35 of the typewriter to which the device is to be mounted.

It is to be noted that certain changes in form and construction may be made without departing from the spirit and scope of the invention.

I claim:—

1. In a device of the class described having a casing, means on said casing for mounting the device on a typewriter comprising a rigid tongue extending from the bottom of said casing, a flexible tongue extending from the top of said casing, said tongues being aligned, studs having sharp-edged upper ends supporting said flexible tongue, a housing enclosing one end of said tongue, said tongue when depressed between said studs deflecting said tongue away from the rigid tongue, a screw shank threadable in said housing having its end rotatably mounted in said tongue, said screw being adapted to deflect the tongue away from the rigid tongue by deflecting the flexible tongue downwardly between the studs, and means for flexing said tongue to decrease the distance between the rigid tongue and the flexible tongue.

2. In a device of the class described having a casing, means on said casing for mounting the device on a typewriter comprising a rigid tongue extending from the bottom of said casing, a flexible tongue extending from the top of said casing, said tongues being aligned, studs having sharp-edged upper ends supporting said flexible tongue, a housing enclosing one end of said tongue, said tongue when depressed between said studs deflecting said tongue away from the rigid tongue, a screw shank threadable in said housing having its end rotatably mounted in said tongue, said screw being adapted to deflect the tongue away from the rigid tongue by deflecting the flexible tongue downwardly between the studs comprising additional studs mounted in said housing above the first-named studs, said additional studs having inclined lower edges and being spaced-apart from the first-named studs.

In testimony whereof I affix my signature.
JOSEPH TIRITTER.
